BUTTER CONDITIONER

Albert F. Wild, Erie, Pa., assignor to General
Electric Company, a corporation of New York

Application January 8, 1942, Serial No. 426,643

3 Claims. (Cl. 312—168)

My invention relates to refrigerator cabinets and more particularly to receptacles or compartments provided within the food storage compartment of refrigerator cabinets for the purpose of maintaining food, such as butter and the like, at a temperature higher than that within the main food storage space of the cabinet.

Many foodstuffs, for proper preservation, must be stored at a temperature lower than that at which butter or the like spreads easily. Thus, when butter is kept in the usual refrigerator cabinet it is necessary that it be warmed up before it is in condition for serving at the table.

It is an object of my invention to provide a new and improved receptacle or compartment constructed and arranged for disposition within the refrigerated compartment of a refrigerator cabinet for maintaining butter or the like kept therein at a temperature which will permit easy spreading thereof.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a partial view of a refrigerator cabinet of the household type provided with a compartment or receptacle embodying the principles of my invention; Fig. 2 is an enlarged partial, perspective, view illustrating some of the details of the compartment shown in Fig. 1; and Fig. 3 is a perspective view, enlarged, illustrating in greater detail the structural features of the compartment shown in Figs. 1 and 2.

Referring to the drawing, there is illustrated a refrigerator cabinet 10 of the domestic type having a food storage compartment 11 arranged to be cooled by a suitable cooling unit or refrigerant evaporator, not shown. The cabinet is of the conventional type employing inner and outer spaced-apart sheet metal walls 12 and 13, respectively with insulation 14 therebetween. An access opening is provided in the front wall and a suitable heat-insulated door 15 is provided for closing the access opening, and the spaces between the inner and outer liners or walls 12 and 13 are closed by suitable heat-resistant non-hygroscopic strips 16.

In order to maintain butter and the like at a temperature above that generally prevailing in the storage space 11 but usually lower than the temperature prevailing exteriorly of the cabinet, 55

I have provided a receptacle or compartment 17. The compartment is preferably situated in the upper front portion of the inner liner 12 on the left-hand side of the food storage compartment and is recessed or disposed in the insulation, the insulation between the outer wall of the compartment and the outer wall or casing 18 of the cabinet being thinned down so that an appreciable amount of heat is conducted through the wall to the compartment. In order to gain access to the interior or the compartment, there is provided a suitably hinged door 19 arranged to be opened into the compartment 17. As will be indicated by a study of Fig. 1, a butter holder or the like may be easily removed from the receptacle 17 without appreciably discommodeing other bottles or articles stored on the upper cabinet shelf.

The receptacle 17 may be formed of any suitable material although a suitable heat conducting material, as porcelain-enamelled steel, for example, is preferred. In the illustrative form of my invention, the receptacle 17 is preferably positioned in the opening of a suitable frame 19 which closes and conceals the space between the receptacle and the inner liner and which may be formed of any suitable material as a plastic, for example. I have provided means for locating and retaining the receptacle 17 in association with the frame 19. The face portion 19a of frame 19 has an opening 20 centrally arranged for the insertion of the receptacle 17, the latter having a turned over marginal rim as indicated by the numeral 21 for engagement with the front face of the frame. The face portion of the frame is provided at its marginal edge with a laterally extending flange 22 constructed and arranged to abut the side wall of the cabinet, as defined by the inner liner 12. In order accurately to locate the receptacle 17 within the opening 20 in the frame, I have provided a plurality of projecting portions extending into the opening 20 for engagement with the walls of the receptacle 17. In the illustrative form of my invention, I have provided extending portions 23 on the lower edge of the opening and an extending portion 24 in the upper front corner of the opening. It will be seen that the projections 23 and 24 will locate the lower and front portions or surfaces of the receptacle 17.

I have provided means for urging the receptacle into engagement with the projections 23 and 24. In the illustrative form of my invention, this means takes the form of a generally circular spring 25 so arranged that the loop por-

tion seats in the upper rear corner of the frame as defined by the face portion 19a of the frame and the flange 22 and the free ends, which are preferably curved or flanged outwardly as indicated by the numeral 26, engage the top and an end wall of the receptacle as shown in Fig. 3. It will be seen that the resilient means 25 will bias the receptacle forwardly and downwardly into firm engagement with the projections 23 and 24.

I have provided means for securing the frame and receptacle with respect to the inner liner 12. This means comprises a long substantially U-shaped spring 27. The free ends of the spring 27 are held at the rear corners of the frame 19 in any suitable manner as by means of grommets or rivets 28 extending through loops 29 in the ends of the spring and suitable openings 30 in the frame. The container 17 is biased into engagement with the frame by means of the engagement of spring 27 and anchor members 31 secured to the top and bottom outer walls of the container 17. The anchor members 31 are disposed laterally of a line through the loops 28 and the take-up members 33 in order to provide the necessary resilient bias.

In order to secure the frame and container at the forward end thereof, the loop portion of the spring extends forwardly well beyond the front end of the frame as indicated by the numeral 32 so that the inner liner 12 may be inserted between the front portion of the flange 22 and the spring portion 32. The inner liner 12 is securely held in this position by means of take-up members 33 which may be in the form of tapped or threaded fastening members extending through suitable openings in the frame and brackets 34 which are secured to the spring 27. By properly dimensioning the bracket 34, it will be understood that the spring will be drawn to the frame, clamping the adjacent portion of the inner liner therebetween.

In order to secure the rear end of the conditioner or receptacle 17 to the inner liner, suitable fastening members as, for example, screws 35 may be inserted through the openings in the grommets or rivets 28 and into suitable threaded cooperation with suitably tapped openings 36 in the inner liner 12.

In order to close the opening to the receptacle 17, there has been provided the cover 18 as hereinbefore stated. The cover is suitably hinged by any desired means along the rear edge thereof as by suitable hinge means 37. The threaded fastening members 35 may conveniently be used to secure not only the frame to the inner liner but also the hinge assembly to the frame. Handle means 38 is provided adjacent the front edge of the cover 18 to facilitate movement of the door or closure member. I preferably employ spring means for normally retaining the cover in the closed position but inasmuch as the details thereof form no part of my present invention, it has been thought unnecessary to describe or disclose the details thereof.

As has been hitherto stated, a certain amount of heat leakage through the wall of the refrigerator next to the receptacle will permit the conduction of a certain amount of heat which is thus made available for raising the temperature of the butter above the box air temperature. I have provided electrical heating means for supplementing the heat leakage into the receptacle. In the form of the invention described and illustrated herein, there is provided a pair of elec-

tric heaters 40 and 41 suitably secured in heat exchange relationship with the ends of the container. Supporting means therefor may conveniently comprise spring clips 42 which hook under clips 43 suitably secured to the container, as by welding, for example. The heating elements are suitably connected in an electric circuit, not shown. In order to control the amount of heat supplied to container or receptacle 17, I have provided a thermostatic device 44, a control knob 45 being associated therewith. Any arrangement of thermostat and control knob may be employed but I have found it to be particularly convenient to provide a control knob which is substantially round and having the edge thereof extending through an opening 46 in the front portion of the frame flange 22, and projecting sufficiently therethrough to enable the user of the refrigerator to operate the control knob by means of the fingers. The knob 45 is suitably attached to a shaft 47 which extends into operative engagement with the thermostatic element within the device 44. In order to support the thermostatic device I have provided a bracket 48 which is preferably of heat conductive material in order to conduct heat from the receptacle walls to the thermostatic device.

In order to provide a substantially uniform degree of heat within the receptacle, I have provided means for deenergizing the heater element slightly before the desired temperature is reached. For this purpose, I dispose a sheet 49 of heat conductive material as brass, for example, between the heater and the thermostat and the receptacle, the sheet thereby being adapted to conduct heat from the heater directly to the thermostat. When the thermostat becomes operative to energize the heating elements, the heater, thermostat, and butter liner are at virtually the same temperature and cooling down. The application of heat to the receptacle wall immediately imparts heat to the plate or strip 49 which proceeds to conduct heat to the thermostat. However, the thermostat temperature rises more rapidly than the receptacle temperature and the thermostat operates to cut out the conduction of current to the heater before the temperature of the receptacle has attained the desired value. In other words, the plate 49 acts as a pre-heat device. Thus the thermostat actually controls the heater and the temperature of the receptacle automatically follows.

The butter or the like and a supporting dish may be placed on the bottom wall of the receptacle, or a shelf 51 may be provided on the inner face of the door 18 for the purpose.

I have illustrated the use of a condenser 50 which may be connected across the contacts of the thermostat in order to minimize radio interference.

While I have shown a particular embodiment of my invention, I do not desire my invention to be limited to the particular construction shown and described and I intend in the appended claims to cover all modifications within the spirit and scope of my invention.

What I claim as new and desire to secure by Letters Patent of the United States is:

1. A storage receptacle for refrigerator cabinets and the like adapted to store butter or the like comprising a frame having an opening centrally disposed therein and a laterally extending flange, a receptacle extending through said opening, a pair of inwardly extending projections extending into said opening from an edge of said

opening and an inwardly extending projection in a corner of said opening opposite the edge from which extend said pair of projections, and resilient means disposed between the remaining corner of the opening opposite the edge from which extend said pair of projections and the associated corner of said receptacle for urging said receptacle into engagement with said projections.

2. In a refrigerator cabinet of the type having spaced inner and outer walls and thermal insulation disposed therebetween, said inner wall having an opening therein, and a food-storage receptacle extending through said opening into the space between said walls, a frame member associated with said receptacle for closing the space between the edge of said opening and said receptacle, and means for attaching said frame and receptacle to said liner, said means comprising a substantially U-shaped resilient member, the free ends of said U-shaped member being secured to said frame at the rear corners thereof and the arm portions of said resilient member extending above and below the receptacle, the closed portion of said member extending forwardly beyond the edge of the frame member, the material defining the edge of said opening adjacent the front edge of the receptacle extending between the flange of the frame and the closed portion of said resilient member, means attached to the upper and lower walls of said receptacle and engaging said arms of said resilient member for biasing said member into the assembled position with respect to said frame, and additional means engaging said resilient member and said frame for drawing said frame and said resilient member into close engagement

with said wall adjacent the front of said frame.

3. In a refrigerator cabinet of the type having spaced-apart inner and outer walls with thermal insulation disposed between, said inner wall having an opening therein, and a food storage receptacle extending through said opening into the space between said walls, a frame associated with said receptacle for supporting said receptacle in said inner wall, means for locating said receptacle with respect to said frame including a plurality of projecting portions extending into the opening in said frame, resilient means urging said receptacle into engagement with said projecting portions, and means for securing said frame and said receptacle to said inner wall, said means comprising a substantially U-shaped resilient member having one arm extending longitudinally above the top wall of said receptacle and the other arm extending longitudinally below the receptacle, the free ends of said resilient member being secured to the frame in the rear corners thereof, the closed end of the U-shaped member extending substantially beyond the front end of said frame, means attached to the top and bottom walls of said receptacle on the outside thereof and engaging said resilient member for resiliently urging said receptacle into the assembled position with respect to said frame, said inner liner adjacent said opening extending between said frame and said closed portion of said resilient member, means for drawing said frame and resilient member together in order to clamp said frame and said member to said inner liner at the front end of said receptacle, and means for securing the rear corners of said frame to said inner wall.

ALBERT F. WILD.
